UNITED STATES PATENT OFFICE.

MAXIMILIAN S. HACHITA, OF WILKES-BARRE, PENNSYLVANIA.

PULSATING JIG.

Application filed November 15, 1923. Serial No. 674,904.

My invention relates to pulsating jigs which are adapted to be employed in the treatment of coal, ore and the like for the purpose of separating the same in accordance with the specific gravities of the different constituents of the mass treated.

An apparatus embodying my invention is particularly well adapted for the treatment of coal of the smaller sizes, such as pea, buckwheat, rice and barley, for the purpose of eliminating therefrom refuse matter such as slate, stone and the like intermixed therewith and which is of higher specific gravity than coal.

One method which is employed in the treatment of materials of the character mentioned to effect separation of the portions of different specific gravities is to cause the same to move forward over the bottom of a pan or receptacle and simultaneously to cause an intermittent or impulse flow of water upwardly through openings in the said bottom; but such practice has not proved satisfactory in all cases, particularly in the case of small sizes of coal such as mentioned above, because of the lack of means for properly controlling the flow of the water through the said materials.

The principal object of the invention, therefore, is to provide means whereby different areas or portions of the material within a pan or receptacle being treated may be subjected to the action of separate columns of water which are flowing upwardly with different forces; that is to say, with different speeds.

In the treatment of materials in the manner suggested by upwardly flowing water, it is desirable that the water be supplied in more or less frequent successive impulses and also that the quantity supplied to different areas or regions may be different and varied in order that the proper suspension in the jiggling medium (water) of the material being treated may be properly controlled whereby stratification in accordance with the specific gravities of the different portions of the said material may be effected. It is, therefore, an object of the present invention to provide means whereby different portions or regions of the material being treated may be subjected to forces within and by the jiggling medium in such manner as to effect the desired stratification and forward movement thereof within the jig and the discharge of the same therefrom.

Other objects and advantages of the invention will be pointed out in the detailed description thereof which follows or will be apparent from such description.

In the accompanying drawings, forming a part of this specification, I have illustrated certain forms of apparatus embodying my invention, but it will be understood that the invention is susceptible of embodiment in other forms of apparatus than those shown and that various changes may be made in the details of construction without departing from the scope of the invention as defined in the claim.

In the drawings:

Fig. 1 is a longitudinal sectional view of an apparatus adapted for the treatment of coal for the elimination of slate, stone, grit and the like therefrom in which my invention has been embodied;

Fig. 2 is a top plan view thereof;

Fig. 3 is a transverse sectional view taken on the line 3—3 of Fig. 1;

Fig. 4 is a vertical longitudinal sectional view of a slightly modified construction of apparatus in which my invention is embodied;

Fig. 5 is a similar view showing another modified construction of apparatus in which the said invention is embodied;

Fig. 6 is a view in longitudinal vertical section showing still another modified construction of jig embodying the invention; and

Fig. 7 is a vertical sectional view taken on the line 7—7 of Fig. 6.

Referring to the drawings: 1 designates a tank having an opening 2 in its bottom which is adapted to be opened and closed by a valve 3 actuated by a lever 4 and connecting rod 5. In the several forms of construction, endless carriers 7 are provided for conveying the coal from the apparatus after the same has been separated from the slate, stone or other material to be eliminated. The slate, stone and other material of specific gravity higher than that of the coal, is conveyed from the apparatus by means of an endless conveyer 8. The endless conveyers 7 and 8 for separately conveying the coal and slate from the apparatus are of known construction and operate in known manner.

Referring now to Figs. 1 to 3, inclusive, of the drawings: 12 designates a screen consisting in the construction shown of a fer-

inous plate which extends across a portion of the tank 1, a considerable distance above the bottom 13 thereof. The said plate 12 is inclined downwardly from the front to the rear and, in effect, constitutes the bottom of a pan or receptacle into which the material, such as coal with its admixture of slate, bone and the like, being treated is discharged from a chute 14 from a source of supply (not shown). The said material is discharged into what is in effect a hopper 14^a and is caused to flow or move rearwardly underneath the gate 15 and over the screen bottom 12.

15 The gate 15 may be adjusted by turning the crank handle 16 and the nut to which it is attached in known manner.

The rear edge or end portion of the plate 12 is supported upon an upright plate 17 or 20 solid wall of other construction. The space between the said wall 17 and the right hand wall of the tank 1 is divided by means of vertically arranged partition plates or boards 18 into a series of compartments 19, 25 20 and 21. The bottoms of these compartments are provided with openings 22 which are adapted to be opened and closed by means of valves 23, actuated by means of handles 24 and connecting rods 25, or in any 30 other preferred manner.

For the purpose of aiding and facilitating the movement of the material, such as coal with its admixture of stone, slate and the like, being treated, means is provided for 35 subjecting the portions thereof directly above the compartments 19, 20 and 21 to successive impulses at proper intervals of upwardly flowing water. The water is supplied to the said compartments through slots 40 27 in the lower sides of horizontally arranged pipes 28, the inner ends of which are closed as shown in Fig. 3, while the outer ends thereof have connection with a manifold 30 having connection with a water supply pipe 31. The pressure of the water as 45 it issues from the pipe 31 is adapted to be controlled by means of a pressure regulating valve 32. For the purpose of causing the water to flow upwardly from the compartments 19, 20 and 21 through the screen 12 in successive impulses of greater or less 50 frequency, a rotatable plug valve 40 is provided between the valve 32 and the manifold 30. The valve 40 is provided with an opening 41 which extends therethrough and also is provided with a stem or shaft 43 which 55 has a wheel 44 thereon, over which a driving belt 45 passes. The said belt is driven by means of a wheel 46 upon the main driving shaft 47 of the apparatus which is driven by 60 means of a driving wheel 48, the latter in turn being driven by a belt or band (not shown). For the purpose of holding the belt 45 tight, an idler wheel 50 is provided. By varying the sizes of the wheels 44 and

46, the speed of rotation of the valve 40 may be varied. As the valve rotates, water is permitted to flow from the supply pipe 31 through the opening 41 into the manifold 30 each time that the said opening is moved 70 into alignment with the passageway within which the valve is situated. It will be seen, therefore, that the water is admitted into the manifold 30 and from the latter into the compartments 19, 20 and 21 in successive 75 impulses and in like manner is delivered from the said compartments through the openings of the screen 12.

In order that the force of the impulses with which the water is delivered from the 80 respective compartments 19, 20 and 21 may be varied and controlled as desired, the pipes 28 which extend into said compartments as heretofore described are each provided with pressure regulating valves 51. By regulating these valves, the pressure of the water within the pipes 28 is controlled and by the regulation of such pressure the amount of water delivered and the force of the successive 85 impulses of its upward flow are varied 90 and controlled.

In the actual operation of the apparatus the amount of water delivered from the compartment 21 may be less than that required to be delivered from the compartment 20; 95 nor is it necessary that the water from compartment 21 shall be delivered intermittently. It is only necessary that sufficient water be delivered to the hopper 14^a or that some means be provided to cause rearward movement of the material under the gate 15. The amount of water delivered from the compartment 20 must be sufficient and delivered at such rate as to cause suspension 100 of the material in the water above the screen. The different materials of the mass being treated being of different specific gravities they range themselves in stratified positions at different heights above the screen 12 and are carried rearwardly by 105 the flow of the water into position adjacent the vertically adjustable gate or valve 55. The coal is of less specific gravity than the refuse matter and consequently collects* in a stratum above the latter. The amount and 110 the speed of the flow of water from the compartment 19 are less than from compartment 20 so that the slate, stone and other refuse matter and the coal settle down upon the screen with the coal constituting the top 115 layer or stratum. 120

The slate, stone and the like of higher specific gravity are discharged underneath the vertically adjustable gate or valve 55 and pass over the upper edge of the vertically adjustable plate 56. Adjustment of the plates 55 and 56 is effected by means of the crank actuated nuts 57, in known manner. The coal or other material from which the slate, stone and the like have been sepa- 130

rated being of lighter specific gravity constitutes the topmost layer of the mass and is discharged over the upper edge of the breast plate 60 and flows downwardly to the lower end of the endless conveyer 7 and is conveyed thereby from the apparatus. The slate which is discharged over the upper edge of the adjustable plate 56 falls into a truncated cone shaped hopper-like chamber from which it is conveyed by the endless conveyer 8. The discharge of the refuse and the coal is caused by the upward flow of the water from the compartment 19. The amount of water delivered from this compartment should be sufficient to effect discharge as stated but should not be sufficient to elevate the slate and cause its discharge with the coal.

Referring now to Fig. 4 of the drawings: It will be noted that the space between the bottom 13 of the tank and the screen 12 of the receptacle for the material to be treated is divided into compartments by means of the vertical partition plates 18 as in Figs. 1 to 3. The compartment or chamber 61 is situated underneath a pivoted gate 62 onto which the slate, stone and the like and the coal to be discharged are deposited, the same having been previously stratified in the manner described in connection with Figs. 1 to 3 with the coal constituting the upper or top stratum. The gate 62 is hinged at 63 and its rear swinging end portion is connected to the lower end of a connecting rod 64. The upper end of the said rod is connected at 65 to a lever 66 pivoted intermediate its ends to a post 67. An adjustable weight 68 upon the said lever tends to hold the gate 62 in closed position with its rear upper edge against the lower edge of a breast plate 70 but in operation the said gate does not rest against the lower edge of the plate 70. The intermittent pulsating flow of the water upwardly from the compartment 61 against the slate, stone and the like and coal resting upon said gate effects discharge of the slate, etc. and the coal and causes a vibratory or swinging movement of said gate. The refuse, consisting of slate, stone and the like, is discharged underneath the lower edge of the breast plate 70 and is delivered into the bottom of the tank 1 and is conveyed therefrom by the endless conveyer 8 in known manner. The coal is discharged over the top of the plate 70 and is removed from the tank by the conveyer 7. In order to permit vertical swinging movements of the gate 62, the upper edge or end of the outer wall 72 of the compartment 61 terminates a distance below the lower edge of the breast plate 70, leaving a considerable gap between the said upper edge of the wall 72 and the lower edge of the plate 70. The said gate is provided with a curved flange 73 which constitutes a closure for the said gap, so as to prevent the outflow of any considerable

portion of water from the compartment 61 through the said gap. It is necessary that the water shall flow upwardly through the perforations in the gate 62 in order that the discharge of the refuse and the coal may be facilitated and properly effected.

The bottoms of the compartments between the bottom 13 and the screen 12 and gate 62 are provided with openings 22 which are adapted to be opened and closed by slide valves 23 which may be operated in any suitable and convenient manner, as by means such as is shown for operating the corresponding valves in Figs. 1 to 3 of the drawings. Water is supplied to the compartments intermediate the screen 12 and the bottom 13 from the pipes 28 through slots 27 in the bottoms thereof, as in Figs. 1 to 3. The water is discharged from these slots intermittently in the same manner as described in connection with the construction disclosed in Figs. 1 to 3 of the drawings.

Referring now to the construction shown in Fig. 5 of the drawings, it will be noted that the space intermediate the bottom 13 and the screen 12 is divided into compartments by means of partition plates 18 and that water is supplied intermittently to the said compartments from pipes 28 through slots 27 in the bottoms thereof as in the previous constructions. These compartments are provided with openings 22 which are controlled by valves 23 which may be operated as previously described.

The mass constituting a mixture of coal, slate, stone and the like, or other material containing relatively heavy impurities to be eliminated is delivered to the jig as in the construction shown in Figs. 1 to 3 of the drawings and is subjected to the action of intermittently flowing water discharged upwardly through the screen 12 from the compartments underneath the same. The coal being the lighter is ultimately separated in the manner as described in connection with Figs. 1 to 3 from the slate, stone or other relatively heavy material, and finally constitutes the upper stratum of the whole mass. The heavier material slides downwardly along the inclined portion 80 which constitutes an extension of the screen 12, underneath the inner or front edge of the adjustable breast plate 81. Adjustment of the said plate is effected by means of an adjustable screw threaded rod 82 which has connection as indicated at 83 with the forward swinging edge of the said breast plate. The coal, constituting the upper stratum of the mass, passes onto the said plate and thence to the conveyer 7 by means of which it is conveyed from the apparatus. The slate, stone and the like are discharged onto the bottom of the tank 1 and are conveyed therefrom by means of the endless conveyer 8.

Referring now to Figs. 6 and 7 of the

drawings, it will be seen that the material to be treated by the jiggling medium is delivered from a chute 14 into the hopper 14^a from which it passes underneath the lower edge of a gate or valve 15 which is adapted to be adjusted by means of a crank 16 and nut to which it is secured. The space underneath the screen bottom 12 of the apparatus is divided by means of upright partition plates or walls 18 into compartments 19, 20 and 21. Water is delivered into these compartments through openings 27 in the lower sides of horizontally extending pipes 28 situated therein. Delivery of the water to these pipes and the control of its delivery therefrom into the compartments 19, 20 and 21 are effected in the manner as described in connection with the preceding figures of the drawings. As the mixture of coal, slate, stone and the like moves rearwardly after it has passed underneath the gate or valve 15 the upward flow of the water from the compartments 20 and 21 effects suspension thereof within the water above the screen bottom 12 so that stratification takes place in accordance with the specific gravities of the different materials as has been previously described. The slate, stone, etc., and the coal finally settle down upon the screen bottom in front of the gate or valve 55 and breast plate 60. The coal, as is usual, rests upon the slate, stone and the like. The slate and other refuse are discharged underneath the gate or valve 55 while the coal, being the lighter and being deposited upon the top of the bed of slate, stone, etc., is discharged over the upper edge of the breast plate 60.

In order that the operator or person in charge of the apparatus may observe the interior of the apparatus for the purpose of ascertaining whether or not proper separation of the coal and the refuse matter is being effected I have provided openings which are closed by transparent material, such as glass, as indicated at 60^a. These openings are shown only in Figs. 6 and 7 but obviously they may be employed in the other forms of construction if desired. If by observation it is ascertained that proper separation is not being effected adjustment of the valves to vary the flow of water through and from the different compartments underneath the screen bottom 12 may be made.

The screen bottom 12 extends rearwardly and slightly downwardly, as indicated at 90, and terminates in a flange-like enlargement, as indicated at 91, against the outer or rear surface of which a vertically adjustable gate 92 is fitted. The said gate is provided with a rod 93 which extends upwardly and to the upper end of which a nut 94 has screw threaded connection. Adjustment of the rod vertically is effected by rotation of the said nut so as to vary the height of the

upper edge of the gate 92. The slate, stone and the like, after they have passed underneath the lower edge of the gate or valve 55, pile up against the front side of the portion of the gate 92 which projects above the rear end portion of the extension 90 of the screen bottom 12.

The amount of water which is permitted to be discharged into the compartment 19 and from the latter upwardly through the portion of the screen bottom 12 which is located thereover should be sufficient to effect discharge of the coal and the refuse as heretofore indicated, but should not be sufficient to move or throw the slate, stone and the like upwardly with sufficient force to cause an admixing of the coal and refuse after the separation thereof as described.

It may happen that the refuse consisting of slate, stone and the like may pile up too high against the front side of the gate 55 and breast plate 60, with the result that it might happen that portions of the slate, etc. would be discharged with the coal over the upper edge of the breast plate 60. In order to prevent this occurrence I have provided means for facilitating and accelerating the discharge of the slate from underneath the gate or valve 55 and over the edge of the gate of stop plate 92. To this end I have provided a valve plate 95 hinged to the upper edge of a rear wall 17^a. Normally the said valve plate 95 is held in vertical position, as indicated in full lines in Fig. 6 of the drawings, with its upper edge portion resting against stops 96 secured upon the under side of the screen bottom 12. The holding of the valve plate 95 in this position is effected by means of a weight 98 adjustably supported upon a lever arm 99, which arm is situated exteriorly of the tank 1 as shown and which is connected at its rear end to the said valve plate. In case the refuse matter should pile up to too great an extent upon the front side of the gate 55 and breast plate 60, so that by reason of its weight it would offer unusual and too great resistance to the passage of water directly upwardly through the screen bottom 12, the reaction would effect tilting or opening of the valve plate 95 toward the left so as to provide a passageway for the water through the extended portion 90 of the screen bottom 12 to the left of the gate 55.

The passage of the water upwardly through the portion 90 of the screen would effect more rapid discharge of the refuse over the upper edge of the gate 92, with the result that more rapid delivery of the refuse underneath the gate 55 would be brought about so that the height or thickness of the bed of refuse material above the screen bottom 12 in front of the said gate 55 and breast plate 60 would be decreased. Upon the decreasing of the thickness and the

weight of the bed of refuse material above the portion of the screen bottom 12 above the compartment 19, the water would again take its usual course upwardly through the 5 said screen bottom while the valve plate 95, under the influence of the weight 98, would be closed or returned to the position as shown in Fig. 6 of the drawings. The said valve plate is indicated by dotted lines in 10 an open position.

It will be seen that the construction as disclosed in Figs. 6 and 7 provides means whereby the height and the weight of the 15 bed of refuse material (slate, stone and the like) above the screen bottom 12 in front of the gate 55 and breast plate 60 are automatically controlled in such manner as to insure that the said refuse will not be discharged over the upper edge of the breast 20 plate 60 and be delivered as an impurity with the coal previously separated therefrom.

It will be noted that in the several forms 25 of construction, the water is discharged downwardly from the pipes which are located in the compartments underneath the screen 12. It is preferable, though not essential to my invention, that the water be discharged downwardly in said compartments so that the force thereof may be 30 spread over substantially the entire cross sectional area of the respective compartments. By thus discharging the water the force of the upward flow from any compartment is substantially uniform throughout 35 the area of the portion of the screen bottom through which it passes. By causing the water to be discharged from the respective compartments with substantially uniform 40 force at all points in the horizontal or transverse area thereof better and more efficient results are obtained in operation.

It will be seen that by my invention I 45 have provided a unitary apparatus having means whereby the water from one of the compartments under the bottom of the separating receptacle or chamber may be caused to flow upwardly with greater speed and force than is the case with the water which 50 is discharged from another or any one of

the other compartments of the apparatus. By thus controlling the speed and force of the water which is admitted to different areas or portions of the separation chamber, I am enabled to effect a much more complete and efficient separation of the slate, stone and the like, particularly in the smaller sizes of coal, than is possible with the ordinary construction in which the water is discharged into the said separation chamber 55 with substantially the same force at all points of the bottom thereof.

Having thus described my invention, what I claim and desire to secure by Letters Patent is:

In a coal jig, the combination of a chamber for receiving the coal with impurities intermingled therewith for washing and separating the same, the said chamber having a bottom provided with openings extending therethrough, a breast plate and adjustable gate at the rear end of said chamber, the said bottom extending rearwardly and beyond the plane of the said breast plate and gate, a stop plate adjacent the rear edge of the said bottom, a compartment situated underneath the said bottom, the rear wall of the said compartment being in substantially the same plane as that of the said breast plate and gate, the upper portion of 70 said wall comprising a gravity controlled gate which is adapted to open outwardly upon pressure from within, and means for intermittently and controllably supplying water to the said compartment, the water 75 from the compartment being adapted, in the event of the impurities and coal banking too high against the breast plate and gate, to re-act against the said gravity controlled gate to open the same whereby water is 80 adapted to flow upwardly through the portion of the said bottom beyond and rearwardly of the plane of the said breast plate and gate, substantially as described.

In testimony that I claim the foregoing 85 as my invention, I have hereunto signed my name this 13th day of November, A. D., 1923.

MAXIMILIAN S. HACHITA.
